ATTORNEYS.

UNITED STATES PATENT OFFICE.

ALFRED H. BEYER, OF CLEVELAND, OHIO.

BOX.

Application filed August 11, 1926. Serial No. 128,675.

This invention relates to boxes, and has for one of its objects the provisions of a simple efficient and economical box.

The box of my invention may be made of 5 any suitable material such as cardboard. Another object of my invention is the provision of means whereby a box may be properly constructed and held together without use of nails, adhesives, etc.

10 With the foregoing objects in view, together with such other objects and advantages as may subsequently appear, this invention resides in the construction and arrangement of parts hereinafter described 15 and claimed, and illustrated in the accompanying drawings, in which

Figure 1 is a perspective view of the box of my invention.

Figure 2 is a plan view of a blank employed in making the box shown in 20 Figure 1.

Figure 3 is a vertical sectional view through a side of the box as being assembled.

25 Figure 4 is a vertical section through the box as assembled and Figure 5 is a broken plan view of an endless band employed to hold together the sides of the box.

Referring to the drawings for a more 30 detailed description thereof, the box of my invention is partly made from the blank 7 shown in Figure 2. This blank is cruciform in plan view and comprises a square central section 8 integral with which are 35 sections 9 and 10, which are respectively to the left and right and sections 11 and 12 are respectively above and below. The sections 9 and 10 are in alignment with each other and are at right angles to the sections 40 11 and 12 which are in alignment with each other. Sections 9 to 12 inclusive are in the same form and are each bent along the lines 15, 16, and 17, whereby sub-sections 18, 19, 20 and 21 are made in each of the sections 45 9 to 12, inclusive.

In forming the box, the sections 18 are bent upwardly at right angles to the section

8 which forms the bottom of the box. The sides of the box, therefore, are sub-sections, 18, 19, 20 and 21. A square band 22, which 50 is in the form of a closed loop is then slipped over the sides of the box, preferably from the bottom to the top of the sides. The sub-sections 19, 20 and 21 are then bent over on the outer sides of the band 22. The 55 sub-sections 20 are then disposed horizontally and the sub-sections 21 are pushed up between the inner faces of the band 22 and the outer faces of the sides 18. The described disposition of the sub-sections 18 to 21 inclusive function to hold the band 22 from falling, while the band, itself, functions to hold the sides 18 together.

It will be noted that sub-sections are tapered. This assists in readily pushing 65 them into the position described in assembling the box.

Figure 5 shows in plan view an endless band 22 reenforced by a strip of cloth 25. The strip of cloth 25 is very thin and provides a reenforcement for the band 22, 70 which may be of cardboard.

While I have described one embodiment of my invention, modifications thereof may be readily devised without departing from 75 the spirit of my invention, and it is to be understood that such modifications come within the scope of the appended claim.

I claim:-

A box comprising a bottom, sides integral 80 with said bottom and upturned therefrom, a flat band in the form of a closed loop around said sides and adjacent the upper part thereof, said band having a width less than the height of the sides, and extensions 85 integral with said sides folded around the upper and lower edges of said band and extending from the lower edge of said band sufficiently upward between the band and the sides to hold the band in place without 90 the use of fastening means, said box being of cardboard.

ALFRED H. BEYER.
